A. DEL GIUDICE.
BINDING ATTACHMENT FOR SEWING MACHINES.
APPLICATION FILED JULY 16, 1918.

1,299,569.

Patented Apr. 8, 1919.

By his Attorneys

Arturo Del Giudice

Inventor

Edgar Gate & Co.

UNITED STATES PATENT OFFICE.

ARTURO DEL GIUDICE, OF NEW YORK, N. Y.

BINDING ATTACHMENT FOR SEWING-MACHINES.

1,299,569.

Specification of Letters Patent.

Patented Apr. 8, 1919.

Application filed July 16, 1918. Serial No. 245,184.

To all whom it may concern:

Be it known that I, ARTURO DEL GIUDICE, a citizen of the United States, and residing at New York, in the county of New York and State of New York, have invented certain new and useful Improvements in Binding Attachments for Sewing-Machines, of which the following is a specification, such as will enable those skilled in the art to 10 which it appertains to make and use the same.

This invention relates to attachments for sewing machines and particularly to a device of this class which is designed for use in 15 binding one or more thicknesses of fabric by a binding strip which is folded by said attachment and stitched thereto by the machine, and the object of the invention is to provide an attachment of the class and for 20 the purpose specified which is adapted for use in connection with workpieces or articles of different thicknesses; and a further object being to provide a tensionally controlled attachment which will adjust itself automatically 25 to workpieces of different thicknesses; and with these and other objects in view the invention consists in a device of the class specified, constructed and operating as hereinafter described and claimed.

30 The invention is fully disclosed in the following specification, of which the accompanying drawing forms a part, in which the separate parts of my improvement are designated by suitable reference characters in 35 each of the views, and in which:

Figure 1 is a plan view of the table of a sewing machine showing my attachment applied thereto and indicating the method of its use;

40 Fig. 2 a view looking in the direction of the arrow 2 of Fig. 1;

Fig. 3 a view looking in the direction of the arrow 3 of Fig. 1 but showing my attachment detached from the machine; and,

45 Fig. 4 a partial section on the line 4—4 of Fig. 3 and showing parts in a different position.

In Figs. 1 and 2 of the drawing, I have indicated at 10 the table of a sewing machine and secured thereto adjacent to and beneath the needle bar and needle of the machine is a binding attachment 11 comprising a main L-shaped body portion 12 having a base 13 and an upwardly directed portion 14. Secured to the main body portion is a bracket device 15 provided with an elongated aper-

ture 16 through which a screw or other fastening device 17 may be passed for securing said bracket and the main body portion 12 to the table 10 of the machine as clearly indicated in Figs. 1 and 2.

Secured to the upwardly directed portion 14 and base 13 of the body portion 12 is a binding tape folding device 18 composed of two parts, a bottom stationary part 19 and a top movable part 20, said parts being separated from each other by a slot or opening 21. The separate parts 19 and 20 are connected at one end as shown at 22 and each of said parts consists of front walls 23 and back walls 24, and the front walls 23 of each of said parts are bent outwardly and inwardly as shown at 25 in Figs. 2 and 4 of the drawing to fold the opposite side edges of a binding strip 26 outwardly and inwardly as indicated in Fig. 2 prior to stitching it onto a workpiece or workpieces 27 by stitchings 28 as indicated in Fig. 1.

Secured to the forwardly directed free end portion of the part 20 or the back wall 24 thereof is an upwardly directed plate 29 having an elongated slot 30 through which passes a rivet 31 which is secured to the upwardly directed portion 14 of the main body part and a finger or keeper 32 is secured to the top portion of the plate 29 and is adapted to support one end of a spring 33, the other end of which is secured to the bracket device 15 as shown at 34 in Figs. 2 and 4 of the drawing.

By providing the movable part 20 of the binding tape folding device and the tensional means shown and described for normally holding said part in a depressed position, a workpiece or workpieces of different thicknesses may be passed through my attachment and bound in the manner above set out without any adjustment of the attachment by the operator, and it will be understood that my invention is not limited to 106 the transverse width of the binding tape 26 employed, nor to the details of construction herein shown and described as various changes therein and modifications thereof may be made, within the scope of the appended claims, without departing from the spirit of my invention or sacrificing its advantages.

The operation of my binding attachment will be the same as other devices of its class 110 now used, a binding strip 26 is fed or threaded through the binder 18 from the

closed end 22 thereof and the end of said tape is passed out through the folded portions 25 and a workpiece 27 is placed in the position shown in Fig. 1 between the separate parts 19 and 20 of the binder 18 and in the slot or opening 21, and between the separate folded sides of the binding strip 26, and said folded strip is stitched by the sewing machine mechanism as indicated at 28 in Fig. 1 in the usual manner and by providing the movable part 20 any variation in the thickness of the workpiece 27 will be automatically taken up as will be readily understood.

15 Having fully described my invention, what I claim as new and desire to secure by Letters Patent, is:—

16 1. A binding attachment for sewing machines, comprising a substantially L-shaped body portion provided with a bracket attachment for connecting the body portion with the table of a machine, a binding strip feeding and folding device consisting of two parts joined at one end, the free end of one of said parts being slidably engaged with said body portion and movable toward and from the free end of the other part secured to the body portion, and tensional means for controlling the movement of said movable part.

20 2. A binding attachment for sewing machines, comprising a main L-shaped body portion provided with a bracket attachment whereby said body portion may be adjustably connected with the table of a machine, a binding strip feeding and folding device consisting of two parts connected at one end in such manner as to permit of the movement of the other end of one of said parts

toward and from the corresponding end of the other part, the free end of the movable part being provided with a raised and slotted member through which is passed a headed pin which is secured to the body portion, and a tensional device secured to the body portion and to said raised and slotted member for controlling the movement of the movable part of the binding strip feeding and folding device toward and from the stationary part.

25 3. A binding attachment for sewing machines comprising a main L-shaped body portion provided with a bracket attachment whereby said body portion may be adjustably connected with the table of a machine, a binding strip feeding and folding device consisting of two parts connected at one end and being bent and tapered to the other or free end, one of said parts being secured to the main body portion at said last named end and the corresponding end of the other of said parts being movable toward and from said first named part, means connected with the free end of the last named part for guiding said part in its movement, and a tensional device secured to said means and to the body portion for controlling the movement of said part toward and from the stationary part.

30 In testimony that I claim the foregoing as my invention I have signed my name in presence of the subscribing witnesses this 13th day of July 1918.

ARTURO DEL GIUDICE.
